UNITED STATES PATENT OFFICE.

FRANK A. LUNDQUIST, OF CHICAGO, ILLINOIS.

REGISTERING DEVICE FOR TELEPHONE-EXCHANGES.

No. 848,328.

Specification of Letters Patent.

Patented March 5, 1907.

Application filed October 20, 1904. Serial No. 229,233.

To all whom it may concern:

Be it known that I, FRANK A. LUNDQUIST, a citizen of the United States of America, and a resident of Chicago, county of Cook, and State of Illinois, have invented certain new and useful Improvements in Registering Devices for Telephone-Exchanges, of which the following is a specification.

My invention relates to registering devices for telephone-exchanges, and more particularly to automatic exchanges in which a calling subscriber performs the operations required in calling some other subscriber. In the use of such exchanges it is usual to charge each subscriber for each call he makes, but not to make a charge if the calling subscriber fails for any reason to receive an answer from the subscriber he calls.

It is the object of my invention to register at each calling-station the calls which are made from it and which are answered by the calling-station, but not to register calls which are not answered. This result is accomplished by placing at each station a registering or counting device and providing it with electrical connections so arranged that the registering device will be operated when the called subscriber removes his receiver from its hook.

In the accompanying drawing I have illustrated the arrangement and operation in the simplest and most convenient manner, though it is to be understood that in large and complicated exchanges other connections than those shown will be required for the successful operation of registration. These other connections do not, however, involve any departure from the invention herein illustrated, but are simply adaptations to the particular form of exchange to which the invention is applied. The left-hand portion of the said drawing illustrates two switching mechanisms forming part of an exchange of the kind shown and described in my Patent No. 606,764, of July 5, 1898, and the right-hand part of the drawing illustrates the two stations connected to these switching mechanisms.

The switching mechanisms consist of wipers P, which are moved over contact-points by magnets A. These contact-points are connected together by banks of wires, as shown, or in any other of the well-known manners. There are as many of these wires as there are switching mechanisms, and each wire is a normal or special wire for a different

switching mechanism, so that connection to a particular wire gives connection to a particular switching mechanism.

At each local station there is a receiver R, which is normally supported upon its hook H, a contact device D, operated by a projection HI on the hook H, a generator G, a ringer Q, and a registering device M, operated by a magnet M, also some contact devices and connections, as shown.

The contact device D consists of a sliding pin carried in a pivoted frame D1. It is so constructed that when the hook H rises as a result of removing the receiver R the frame D' turns on its pivot sufficiently to permit pin D to make electrical connection with a contact-spring 18. When the hook H descends, the pin slides endwise to again make connection with the same spring and also with an adjacent spring. This last action relates to releasing the moved switching mechanism and has no direct bearing on the present application.

The registering device M consists of any one of the commercial counting devices. A convenient form has mounted on a spindle a series of wheels each having figures from "0" to "9." When the spindle is turned, the wheels advance step by step, indicating one number higher each step. On the spindle of the registering device M is a ratchet-wheel M². The magnet M' is provided with an armature-lever and pawl, operating upon the ratchet-wheel M². These parts are so arranged that each time an electrical impulse passes through the magnet M' to operate it the registering device is operated so that it will indicate one more than it indicated prior to the flow of such an impulse.

Assuming that a subscriber at the station illustrated in the lower part of the drawing wishes to talk to the subscriber at the station illustrated in the upper part, he removes his receiver and presses key 3. A current then flows from battery X at central ground 1-2.3. 4.5.H.6.A.7.X. This operates magnet A and moves its switch. The subscriber repeats this until the contact-maker P of his switch is in connection with the particular line which is connected to the base or mass of the switch he wants. The drawing shows the calling-switch moved to this connection. The subscriber then operates his generator, when a current flows G-8-6-A-7-A of the called switch 6-H-9-10-Q-11-12-13-mass of called switch 14-15-16-P-mass of calling-switch 13-12-11-

G. This calls the subscriber, who removes his receiver. Upon the rising of the hook H the projection H' in passing presses the pin D momentarily into contact with the spring 18, when a current flows: X-ground to the called station 1-17-D-18-11-12-13-called switch-14-15-16-calling - switch 13-12-11-19-M'-20-21-H-6-A-7-X. The magnets A are of low resistance; whereas the magnets M' are of high resistance. When a magnet A and a magnet M' are in series, as in the circuit just described, the magnet M' will be operated; but its resistance will be sufficient to prevent the operation of the low-wound magnet A. As a consequence of this the removal of the receiver at a called station will cause a registration at the calling-station, but will not cause a registration at any other station. It will be quite apparent that there will be no registration at the calling - station unless the subscriber at the called station answers the call. The further operations of the exchange, such as release of the mechanism, &c., are not any part of the present invention and need no explanation.

25 They are assumed, however, to be substantially the same as shown and described in my before-mentioned patent.

What I claim is—

1. The combination with the stations and 30 the central office of an automatic telephone-exchange, of an electrically-operated switching mechanism at the central office for each local station, means by which a subscriber at his local station may operate his switching mechanism so as to complete connections from his own station to any of the other stations in the exchange, and a registering device at each local station arranged to be operated by a response received from the selected 40 station.

2. The combination with the stations of a telephone-exchange, of an electrically-operated registering device at each station, means by which a subscriber at any one station, may place his registering device in connection with a selected one of the other stations, and automatically-operating means by which upon a response being received from the selected station an impulse will be 50 sent through the electrically-operated registering device of the calling-station.

3. The combination with a series of local stations each of which is provided with an electrically-operated switching mechanism 55 located at a central office, and means controlled from each station for operating its switching mechanism so as to select and signal a desired one of the other stations, of a registering device at each local station, and 60 means by which a response received from the selected station will cause an automatic operation of the registering device at the selecting-station.

4. The combination with a series of local 65 stations, a switching mechanism at a central

office for each station, interconnecting wires for said switching mechanisms, and means controlled from each station for shifting its switching mechanism to any desired interconnecting wires so as to complete electrical 70 connections from a calling to a desired one of the other stations, of an electrically-operated registering device at each station, an electrical connection from one side of each registering device to the associated switching mechanism, a battery at the central office and a receiver-hook at each local station, another connection from the other side of each registering device to said battery, said last-mentioned connection being open when 75 the receiver-hook is depressed and closed when the hook is elevated, and means by which each hook in moving from its depressed to its elevated position temporarily closes a connection between said battery and 80 the interconnecting wire which is normal for that station.

5. The combination with a series of local stations, a switching mechanism at a central office for each station, a normal wire for each 85 switching mechanism, and means controlled from each station for connecting its switching mechanism to any of the other normal wires, of a registering device at each station provided with connections to the switching 90 mechanism thereof, and means by which upon a subscriber at any station responding to a signal delivered thereto an electrical impulse will flow over the normal wire of the responding station and cause an operation 95 of the registering device belonging to the station which has connected its switching mechanism to that wire.

6. The combination with the local stations and the electrically-operated switching mechanisms of an automatic telephone-exchange, 100 of a registering device at each local station, and means by which the registering device of a calling-station is operated by a response 105 being received from a called station.

7. The combination with the stations of a telephone-exchange, means for completing telephonic connections between a calling and a called station, and a device at each station for registering the calls originating thereat, 110 of a battery and devices so arranged that said battery will remain inactive except at such times as short impulses are sent therefrom, and means by which upon the completion of telephonic connection between a calling and a called station one such short impulse from said battery will cause an operation of the registering device at the calling-station.

8. The combination with the stations of a telephone-exchange, and a battery and devices so arranged that said battery will remain inactive except for short impulses sent therefrom, of a registering device at each station for indicating the number of calls originating thereat, and automatic means actu- 115 120 125 130

ated by an impulse from said battery for operating the registering device of a calling-station when a response is made by the called station.

5. The combination with the stations of a telephone-exchange, switching mechanisms by which calling and called stations are placed in telephonic connection with each other, and a registering device at each station for indicating the calls originating thereat, of a battery, devices for sending short impulses therefrom, means by which said battery is inactive at times other than those when short impulses are sent, means by

which impulses sent from said battery serve 15 to operate said switching mechanisms so as to place calling and called stations in telephonic connection with each other, and means by which an extra impulse sent from said battery will operate the registering device of the calling-station. 20

Signed at Chicago, Illinois, this 14th day of October, 1904.
